CARBURETOR

John Francis Butler, Holywood, and William Bruce McCausland Killen, Belfast, Northern Ireland

Application July 10, 1942, Serial No. 450,452
In Great Britain July 29, 1940

5 Claims. (Cl. 261—48)

This invention relates to carbureting devices for internal combustion engines using liquid fuel of the type in which a jet or jets for fuel enter an air inlet pipe at a point where reduction of the area of the pipe causes a local increase of air velocity through the pipe and the consequent reduction of air pressure in the pipe is used to draw fuel into the air stream and thence into the engine.

In known devices of this kind all or the greater portion of the air used for combustion is drawn through the restricted pipe into which the fuel flows and control of engine power and speed is effected by means of a throttle valve between the fuel jet or jets and the engine.

An object of the invention is to provide a carbureting device wherein an emulsion of fuel and air is introduced into the air stream at a position or positions where the air is flowing at high speed through a relatively small passage of Venturi shape of which the outer end is open to the atmosphere or to a point in the engine air supply system upstream of the throttle valve and the inner end opens into the engine main air inlet pipe preferably on or near the central axis of the said pipe at a point where the air velocity and consequent reduction of air pressure is sufficient to promote the required air flow through the said venturi but is not necessarily greater than the general velocity and reduction of pressure through the inlet pipe. Control of engine power and speed is effected by means of a throttling device controllable by the operator of the engine in the engine main air inlet pipe at a position between the end of the venturi where it enters the engine main air inlet pipe and the end of the engine air inlet pipe where it is open to the atmosphere, working in conjunction with means for varying the amount of fuel in the emulsion entering the Venturi passage consisting of valves varying the effective area of passages connecting a chamber into which a fuel jet discharges with the said venturi and with a position at which the air pressure is higher than at the said position in the venturi.

There may also be a jet or jets admitting fuel to other positions in the carbureting device and the flow of fuel through these jets may or may not be controlled by means connected with the throttling device.

The carbureting device according to this invention may be used in conjunction with an engine supercharger placed either between the carburetor and the atmosphere or between the carburetor and the engine.

In the accompanying drawing a constructional example of the invention is illustrated.

Figure 1 shows an axial section through a carbureting device according to the invention.

Figure 2 shows another axial section taken at right angles to that shown in Figure 1.

Fig. 3 is a section detail view of a modified form of control valve for use in the arrangement shown in Fig. 1 instead of that shown at the left hand of said figure.

Fig. 4 is a sectional detail view showing a further form which may be taken by the valve plunger at the left hand side of Fig. 1.

Fig. 5 is a sectional detail view of a further form of the valve plunger at the left hand side of Fig. 1.

Fig. 6 is a sectional detail view of a modification of the fuel jet at the right hand side of Fig. 1.

20 Referring to Figs. 1 and 2 of the drawing:

The carburetor comprises a Venturi passage 1 connected at its upper end to the U-shaped passage 2 which is open to atmosphere and at its lower end to the engine air supply pipe 3 connected to the engine. The engine air supply pipe 3 is directly connected at its upper end to the atmosphere and contains a throttle valve 4 which is controllable by the engine operator, by means not shown, for varying the power output of the engine.

There is provided a float chamber 7 in which the fuel is kept at a constant level in known manner by a float 8, bell crank lever 8^a and needle valve 9. From the float chamber 7 the fuel flows 35 through the passage 10 to jets 11 and 12.

The liquid fuel jet 11 is provided in a sleeve 16 screwed into the bore 16^a and is controlled by a taper needle 13 on a plunger 14 which has fuel passages or flutes 14^a registering with the holes

40 15 in the sleeve, which holes communicate with an annular space 16^b surrounding the sleeve 16 and connected by the passage 6 to the downstream end of venturi 1. The holes 15 are located above the level of the fuel in the float chamber so that

45 they do not come into operation and supply fuel until the engine speed has increased the depression in the main air inlet pipe 3 to a predetermined amount. The plunger has a head 16^c urged upwardly by a compression spring 16^d into contact with an arm of a rocking lever 27.

The jet 12 is provided at the foot of a sleeve 33 screwed into a bore 34 and the jet enters the chamber 17 of which the upper surface is formed by the bottom of a plunger 19 slidable in the sleeve 33. The plunger 19 consists of upper and

lower cylindrical parts 19^d, 19^e and an intermediate waist 19^f, of which the cross sectional shape may vary either uniformly or otherwise from that of the cylindrical parts 19^d, 19^e so that, for example, the longitudinal cross section of the waist is of double concave shape. The plunger has an axial passage 18 extending from the chamber 17 at the bottom thereof to the cross passage 18^a which opens to atmosphere. The head 19^e of the plunger is engaged and urged upwardly into engagement with the rocking lever 27 by the spring 19^h. The chamber 17 communicates with another chamber 20 formed by the waist 19^c and sleeve 33 through holes 21 and 22 and annular space 23 between the sleeve 33 and bore 34. Chamber 20 communicates with the atmosphere through holes 24 in the sleeve and with venturi 1 by means of holes 25 and annular passage 25^a in the sleeve 33 and passage 5.

The throttle 4 has attached to it a cam 26 engaging an arm of the rocking lever 27.

The rocking lever 27 is mounted on an eccentric bush 28 attached to the lever 29.

In operation fuel passes from the float chamber 7 through passage 10 to the jet 11 through which it passes, and up to the flutes 14^a, through the holes 15 into the space 16^b and thence through passage 6 into the air stream near the outlet end of the venturi 1.

Fuel also passes from the float chamber 7 along the passage 10 and through the jet 12 into the chamber 17. This chamber is in communication with the atmosphere through the passages 18 and 18^a. A mixture of air and fuel passes from the chamber 17 via holes 21, space 23 and holes 22 to the chamber 20. Here it mixes with more air which enters by the holes 24 and then passes into the top of the venturi and so into the airstream by the holes 25, passage 25^a and passage 5. It will be seen that vertical movement of the plunger will vary the effective area of the holes 22 and 24. As the throttle 4 is opened from the substantially closed position shown the lever 27 will depress the plunger 19 and will decrease the effective area of holes 24 and increase that of the holes 22. Thus the supply of air through the holes 24 will be decreased and the supply of air-fuel mixture through the holes 22 will be increased. At the same time the plunger 14 will rise under the spring action and progressively open the jet 11 and commence or increase the supply of fuel through the passage 6. Thus variation in the amount of air flowing to the engine through the inlet pipe 3 effected by movement of throttle 4 is accompanied by variation of the amount of fuel flowing to the engine through jets 11 and 12.

With the throttle 4 stationary, movement of the lever 29 and bush 28 causes a movement of lever 27 and varies the relative positions of the plungers 14 and 19 and thus varies the proportion of fuel to air in the mixture supplied to the engine. It will be understood that the spring 19^e will be stronger than the spring 16^d so as always to keep the lever 27 in engagement with the cam 26.

Fig. 3 indicates an arrangement similar to Fig. 1 except that the valve plunger 19^a has the lower part and the passages 18 omitted so that control of the supply of fuel-air emulsion is effected solely by control of the air ports 24. Otherwise the operation is the same as in Fig. 1.

Fig. 4 shows a further modification of the arrangement of Fig. 1, in which the upper part of the waist is cylindrical below the shoulder 30 and

thus control of the supply of fuel-air emulsion is effected solely by control of the ports 22 but otherwise the operation is the same as in Fig. 1.

Fig. 5 shows a further modification in the form of the plunger 19, in which the valve plunger waist 19^f is formed with a central cylindrical portion and two frusto-conical parts 31, 32 so spaced as to act consecutively on the respective ports 22 and 24, the ports 22 being fully open while the ports 24 are being varied and vice versa. It is to be understood that the forms of the plunger 19 shown in Figs. 1, 3, 4 and 5 are only by way of examples and that the shape of the waist 19^f, may be varied in any desired manner to suit the fuel demands of the engine for varying throttle openings.

Fig. 6 shows a modification of the jet 11 of Fig. 1 in that the control needle valve is omitted to give a more or less constant supply of fuel. This constant jet form may be used in combination with the fuel-air emulsion jet as shown in Figs. 1, 3, 4 or 5.

The carburetor as described offers several technical advantages over existing practice. The following are some of these advantages:

(a) Provision of weak mixture at part throttle openings for economy. By arranging the small venturi so that the air flow through it is controlled by the pressure drop across the throttle 4, a limiting air speed and depression is reached in the low pressure zone at a lower engine speed than the normal running speed for the throttle opening concerned. As the engine speed increases from that giving limiting air speed in the small venturi to normal running speed the amount of fuel discharged from the main jet remains unaltered while the amount of air passing through the main air inlet continues to increase, so the mixture becomes progressively weaker.

(b) provision of correct mixture at full throttle at all speeds by controlling the flow from the main jet 12 by means of variable area air bleed 24 and associated mixture passages.

(c) Provision of correct mixture at full throttle at low speed by means of low air pressure in the small venturi 1. If the main air passage 3 were reduced in area to give as great a reduction of pressure in itself, full speed performance would be penalised by the consequent reduction of air flow.

(d) Promotion of good mixing and distribution by concentration of rich mixture from the venturi 1 in the centre of the main air passage 3. This advantage would be nullified if the throttle 55 were located downstream of the Venturi outlet because the mixture would then have to go round the edges of the throttle valve.

(e) Fine pulverisation of fuel droplets by means of high air speed in the small venturi 1. (At part throttle this air speed is controlled by the pressure drop across main throttle valve 4.

(f) Improvement of conditions for starting. The upstream position of the main throttle valve 4 obviates the need for a separate strangler. Rich mixture is obtained by operation of the separate mixture control. The advantage of this is that with the mixture control set at "rich" as the throttle is opened the mixture graduates to normal and danger of cylinder wear due to liquid fuel reaching cylinder walls is reduced.

What we claim is:

1. A carbureting device for internal combustion engines using liquid fuel comprising a body member, a main air supply conduit in the body member in communication with an air supply, an

operator controlled throttle valve in the conduit, a secondary air supply Venturi conduit having an inlet end in connection with an air supply independently of control by said valve, an intermediate zone of restricted cross sectional area and low pressure and a discharge end located downstream of said throttle valve in and surrounded by and facing downstream of the main air supply conduit, means for supplying an emulsion of fuel and air to said zone which comprises a guide bore in said body, a valve plunger slidably guided in said bore and including end parts which are a close sliding fit in said bore and an intermediate waist of reduced varying cross section, a first chamber formed by an end of said bore and one of said end parts, a liquid fuel jet of constant area discharging into said chamber, a second chamber formed by the wall of said bore and the surface of said waist, a first and second port in the wall of said bore respectively in the first and second chamber, passage means connecting said ports, a second and third passage means respectively from a source of air at higher pressure and from said restricted zone, a third port and fourth port in the wall of the bore forming part of the second chamber respectively being terminations of said second and third passage means and a fourth passage means independent of controls by the throttle between a source of air at a higher pressure and said first chamber, and connection means between said throttle valve and valve plunger to cause simultaneous operation thereof to maintain the supply of fuel and air in the relative desired proportions, the axial movement of the plunger causing the wall of the waist part to vary its proximity to and consequent control of said second and third ports.

2. A device as claimed in claim 1, in which said waist has oppositely tapering parts located to cause simultaneous and opposite control of the second and third ports.

3. A device as claimed in claim 1, in which said waist has two oppositely tapering parts located to cause opposite and consecutive control of said second and third ports.

4. A device as claimed in claim 1, including a float chamber and having additional means for supplying fuel comprising a further guide bore in said body member, a fuel jet communicating therewith, a slidable member in said bore having a needle valve controlling said jet and a body portion having grooves, an outer chamber communicating at a level above the fuel level in the float chamber through said grooves with said jet, and a conduit from said outer chamber to the downstream end of said Venturi conduit, and wherein said connection means comprises a lever having one end engaging said plunger valve and the other end engaging said slidale member, an eccentric pivot for said lever intermediate

the ends, an operative connection between said lever and the throttle valve and means for adjusting said pivot to adjust the relative simultaneous positions of said throttle valve with reference to those of said plunger and needle valve.

5. A carbureting device for internal combustion engines using liquid fuel comprising a body member, a main air supply conduit in said body in communication with an air supply, an operator controlled throttle valve in said conduit, a secondary air supply Venturi conduit having an inlet end in connection with an air supply independently of control by said valve, an intermediate zone of restricted cross sectional area and lower pressure and a discharge end located downstream of said throttle valve in and surrounded by and facing downstream of the main air supply conduit, a float chamber for supplying fuel, means for supplying an emulsion of fuel and air to said zone which comprises a guide bore in said body, a valve plunger slidably guided in said bore and including a part which is a close sliding fit and a part having a reduced cross section which varies in the direction of movement of the plunger, chamber means formed by the bore and the end of said plunger, a fuel jet of constant area discharging into said chamber means, a passage between said zone and chamber means and a second passage independent of the throttle valve between said chamber means and a source of air at a higher pressure, a port at the termination of said second passage located for control by said part of reduced cross section which varies its proximity to and control of said port as a result of longitudinal movement of the plunger, additional means for supplying fuel which comprises a further bore guide, a fuel jet communicating therewith, a member slidably guided in said bore, a needle on said member for controlling said jet and a body portion having grooves, an outer chamber round said bore, port means between said bore and outer chamber located above the level of the fuel in the float chamber and communicating with said jet by means of said grooves, and passage means between said outer chamber and the downstream end of said Venturi conduit, and a connection between the throttle valve, plunger and slidale member comprising a rocking lever respectively engaging said plunger and slidale member at opposite ends, an intermediate eccentric pivot for the lever, a connection between said throttle valve and lever to cause simultaneous operation of said throttle valve, plunger and slidale member and means for adjusting said pivot to adjust the relative simultaneous positions of said plunger and slidale member with reference to that of the throttle valve.
